[57] CLAIM

The ornamental design of a housing for a beverage dispenser, as shown and described.

DESCRIPTION

FIG. 1 is a top, left, front perspective view of a housing for a beverage dispenser showing our new design;
 FIG. 2 is a front elevational view of the housing for a beverage dispenser of FIG. 1;
 FIG. 3 is a top plan view of the housing for a beverage dispenser of FIG. 1;
 FIG. 4 is a rear elevational view of the housing for a beverage dispenser of FIG. 1;
 FIG. 5 is a bottom plan view of the housing for a beverage dispenser of FIG. 1; and,
 FIG. 6 is a left side elevational view of the housing for a beverage dispenser of FIG. 1.
 The broken line showings are for environmental purposes only and form no part of the claimed design.
